UNITED STATES PATENT OFFICE.

WILLIAM R. HOCK, CATASAUQUA, PENNSYLVANIA, ASSIGNOR OF ONE-HALF TO JAMES SEYFRIED, OF SAME PLACE.

SCRUBBING-BRUSH.

SPECIFICATION forming part of Letters Patent No. 320,436, dated June 16, 1885.

Application filed October 14, 1884. (No model.)

To all whom it may concern:

Be it known that I, WILLIAM R. HOCK, of Catasauqua, in the county of Lehigh and State of Pennsylvania, have invented certain new and useful Improvements in Scrubbing-Brushes, and I do hereby declare that the following is a full, clear, and exact description thereof, which will enable others skilled in the art to which it appertains to make and use the same, reference being had to the accompanying drawings, which form a part of this specification, and in which—

Figure 1 is a perspective view of my improved scrubbing-brush. Fig. 2 is a sectional view of the same on the line marked, *x-x*, and Fig. 3 is a detail view of the two parts of the hinge-clamp separated from each other.

Similar letters of reference indicate corresponding parts in all the figures.

20 My invention has relation to mops or scrubbing-brushes for cleansing the floors of dwellings, &c.; and it consists in the improved construction of the same, which will be hereinafter more fully described, and particularly pointed out in the claim.

In the accompanying drawings, A denotes the body or back piece of the brush, (shown at B). Upon this is fastened by screws C two castings, which, when put together, form a bearing or a ball socket for the handle D, the lower end of which is inserted into a socket, E, which is cast with a sphere or ball, F, at its lower end. This ball fits with its sides into the hollow cheeks G G, which are cast with plates H, having arms I, the outer ends of which are slotted at *i* for the insertion of the screws C, by means of which the blades or castings H are fastened to the body of the brush.

40 The socket E, with its ball F, is free to move in the slot J, formed between the cheeks GG, and if through wear the play of the ball be-

comes too great, so as to make the brush too loose at the end of its handle, this may readily be remedied by loosening the screws of one 45 or both of the half parts or plates H, and moving it or them closer up against the ball, after which it is again fastened to the body A of the brush. The straight guide edges *g* of the recessed cheeks G prevent the handle from 50 working out of its plane in the direction of the slot or opening between the cheeks, but at the same time permits the handle to turn readily in its bearing without chafing the hands of the person using the brush.

55 I am well aware that a so called "universal" joint or ball-joint is not new, the same being used for a variety of purposes; but I am not aware that a hinge of this class has been made before of the specific construction and for the 60 purpose stated by me in the foregoing specification, whereby wear may be easily compensated for, while at the same time, by the peculiar construction of the plates H, with their radial slotted arms I, the device operates to 65 strengthen the back part or body of the brush by forming diagonal braces for the same.

Having thus described my invention, I claim and desire to secure by Letters Patent of the United States—

70 In a scrubbing-brush, the combination of the brush A B, plates or castings H, having recessed cheeks G, and slotted diverging arms I, and handle-socket E, having a ball, F, at its lower end, substantially as and for the 75 purpose herein shown and specified.

In testimony that I claim the foregoing as my own I have hereunto affixed my signature in presence of two witnesses.

WILLIAM R. HOCK.
